DESIGN FOR A SPECTACLE TEMPLE PIECE

Eric Barrett and Altina Barrett,
Beverly Hills, Calif.

Application November 25, 1944, Serial No. 116,541

Term of patent 14 years

(Cl. D57—1)

To all whom it may concern:

Be it known that we, Eric Barrett and Altina Barrett, citizens of the United States, residing in Beverly Hills, in the county of Los Angeles and State of California, have invented a new, original, and ornamental Design for a Spectacle Temple Piece, of which the following is a specification, reference being had to the accompanying drawing, forming part thereof.

Fig. 1 is a perspective view of a spectacle temple piece, showing our new design.

Fig. 2 is a side elevational view of the spectacle temple piece shown in Fig. 1.

We claim:

The ornamental design for a spectacle temple piece, as shown.

ERIC BARRETT.
ALTINA BARRETT.
